UNITED STATES PATENT OFFICE

114,555

DESIGN FOR A CONTAINER TO BE MOUNTED ON A BICYCLE

John R. Morgan, Oak Park, Ill., assignor to Sears,
Roebuck and Co., Chicago, Ill., a corporation
of New York

Application November 18, 1938, Serial No. 81,203

Term of patent 7 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Container to be Mounted on a Bi-
cycle, of which the following is a specification,
reference being had to the accompanying draw-
ing, forming a part thereof.

Fig. 1 is a top plan view of a container to be
mounted on a bicycle embodying my new design.

Fig. 2 is a side elevational view of the same.

Fig. 3 is a rear elevational view taken from the
position indicated by line 3—3 of Fig. 2.

I claim:

The ornamental design for a container to be
mounted on a bicycle, as shown.

JOHN R. MORGAN.
